Roscoe Ratcliffe
By his Attorney
M. L. Kelly.

UNITED STATES PATENT OFFICE.

ROSCOE RATCLIFFE, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

FUSE-BOX.

1,224,118.

Specification of Letters Patent.

Patented Apr. 24, 1917.

Application filed August 14, 1916. Serial No. 114,700.

To all whom it may concern:

Be it known that I, ROSCOE RATCLIFFE, a citizen of the United States of America, residing at New Britain, Hartford county, 5 Connecticut, have invented a new and useful Fuse-Box, of which the following is a specification.

My invention relates to fuse boxes, and the object is to provide certain new and useful features of construction for the protection of the circuit and the fuses, and also to guard or protect the interior of the box when the fuses are not in place. The above and other objects and advantages will be 15 clear upon a reading of the following description, and an examination of the accompanying drawings.

In the drawings:

Figure 1 is a front view of the box when 20 the fuses are in place.

Fig. 2 is a view of the underside of the same, and partly in section on the line 2—2, Fig. 1.

Fig. 3 is an end view of the box partly 25 open and partly broken away.

I have shown and will describe only one preferred form of my invention.

1 represents the box portion usually formed of sheet steel. 2 represents the 30 cover portion also usually formed of sheet steel. The cover is hinged to the box at 3—3. The box cover 2 is provided with a suitable opening or openings, two being shown in the drawings at 4—4. These openings correspond closely in size to the fuse plugs 5—5. 6 represents the base block of any suitable form or pattern which may be provided with any suitable electric terminal means to which the circuit wires, not shown, 35 may be connected, so that when the fuses are in place, the circuits will be completed. 7 is a slide mounted on the cover 2 and being guided by suitable pin and slot connections therewith. In this instance, the pins are 40 carried by the cover and are indicated at 8—8, while the slots are formed in the slide 7. 9 is a lug carried by the box 1 and arranged to project through a slot 10 in the cover when the latter is closed. The slide 7 45 is provided with two slots, one of the same registering with the slot 10 when the slide is in the position shown in Fig. 1. The other slot in the slide is arranged to register with the slot 10 when the slide is in the 55 dotted line position shown in Fig. 1. It thus

appears that by this arrangement when the cover is closed the projection 9 will pass not only through the cover slot 10, but also through one of the slide slots, whereby the slide is held against movement when the box 60 is closed. A suitable padlock or seal may be employed to lock the box closed, a padlock being indicated at 11.

When the fuses are in place, it is desirable that the same should be exposed for observation and easy access. To that end the slide 7 should be locked in the position shown in Fig. 1, in solid lines. Should the fuses be removed, for example, by the company furnishing the current, as in the event of a discontinuance of service, the company representative may move the slide 7 to the position indicated in dotted lines, Fig. 1, wherein said slide will stand over the openings 4—4 so as to prevent anyone from stealing 75 current by inserting fuses so as to close the circuit, or by tapping into the supply circuit in any way through the openings 4—4. The slide performs the further function of 80 protecting the interior of the box from dust and dirt. While it is preferable to have the slide nearly, or entirely, cover the openings, its most important function first above referred to, will be accomplished if it projects over the openings 4—4 sufficiently to 85 prevent the introduction of fuses. The interior of the box will at all times be protected from dust or dirt either by the presence of plugs 5—5 which practically fill the openings 4—4, or by the slide when the plugs are 90 removed.

I apprehend that various changes and modifications may be resorted to without departing from the spirit and scope of my invention, for example, the slide may be arranged either externally or internally of the cover, such a change or mere reversal being too obvious to require separate illustration. It is also obvious that the interior of the box or cover may be provided with the usual 95 insulating lining, such practice being commonly employed in all types of electric receptacles.

What I claim is:

1. A fuse box comprising a box portion 105 for containing a base block designed to removably receive a fuse, a cover portion hinged to the box portion and having an opening arranged in line with a fuse when in place, a slide carried by said cover and 110

- arranged when in one position to project over said opening, and when in another position to uncover said opening, and means to lock said slide in either position by the act 5 of closing said cover.
2. A fuse box comprising a box portion for containing a base block designed to removably receive a fuse, a cover portion hinged to the box portion and having an 10 opening arranged in line with a fuse when in place, a slide carried by said cover and arranged when in one position to project over said opening, and when in another position to uncover said opening, and means 15 to lock said slide in either position by the act of closing said cover, said means comprising a projection on the box arranged to engage the slide and block its movement when the cover is closed.
- 20 3. A fuse box comprising a box portion for containing a base block designed to removably receive a fuse, a cover portion hinged to the box portion and having an opening arranged in line with a fuse when 25 in place, a slide carried by said cover and arranged when in one position to project over said opening, and when in another position to uncover said opening, and means to lock said slide in either position by the act 30 of closing said cover, said means comprising a projection on the box arranged to engage the slide and block its movement when

the cover is closed, with means to coöperate with said projection to lock the cover closed.

4. In a device of the character described, 35 a box portion arranged to receive a fuse support within the same designed to removably hold a fuse plug, a cover hinged to said box and having an opening in line with said fuse support, a slide mounted on said box 40 cover and arranged to project over said opening when in one position and uncover said opening in another position, with means carried by the box to lock said slide against movement when the cover is closed, 45 and to leave said slide free to be moved when said cover is opened.

5. In a device of the character described, 50 a box portion arranged to receive a fuse support within the same designed to removably hold a fuse plug, a cover hinged to said box and having an opening in line with said fuse support, a slide mounted on said box cover and arranged to project over said opening when in one position and uncover 55 said opening in another position, with means carried by the box to lock said slide against movement when the cover is closed, and to leave said slide free to be moved when said cover is opened, the opening in the box 60 cover corresponding substantially in size and shape to the end of a fuse plug.

ROSCOE RATCLIFFE.
